TRUCK

Joseph F. Joy, Claremont, N. H., assignor to
 Sullivan Machinery Company, a corporation
 of Massachusetts

Application May 27, 1936, Serial No. 82,154

17 Claims. (Cl. 105—161)

This invention relates to trucks, and more particularly to improvements in transport trucks for coal mining machines.

An object of this invention is to provide an improved transport truck for a coal mining machine. Another object is to provide an improved transport truck for a coal mining machine whereby the truck may be propelled by the power of the mining machine supported thereon. A further object is to provide an improved transport truck for a coal mining machine having improved driving connections between the mining machine and the truck wheels. Still another object is to provide an improved automatic coupling mechanism between a driving element on the machine and a cooperating driving element on the truck, whereby when the machine is moved into transport position onto the truck, the driving elements are automatically coupled together. A still further object is to provide an improved cable reel for the power conductor cable of the mining machine motor, and improved driving and controlling means for the cable reel. These and other objects and advantages of the invention will, however, herein-after more fully appear.

In the accompanying drawings there is shown for purposes of illustration one form which the invention may assume in practice.

In these drawings—

Fig. 1 is a plan view of the illustrative embodiment of the improved transport truck.

Fig. 2 is a side elevational view of the improved truck shown in Fig. 1, with a coal mining machine shown in transport position thereon, as indicated in construction lines.

Fig. 3 is a cross sectional view taken substantially on line 3—3 of Fig. 2.

Fig. 4 is an enlarged view in longitudinal section showing the improved automatic coupling mechanism together with the cooperating elements of the machine and truck, the view taken in the plane of line 4—4 of Fig. 1.

Fig. 5 is a fragmentary sectional view taken in the plane of Fig. 4, showing parts of the coupling mechanism in a different position.

Fig. 6 is an enlarged view in longitudinal section taken substantially on line 6—6 of Fig. 1.

Fig. 7 is an enlarged fragmentary vertical sectional view taken in the plane of Fig. 6, showing details of the cable reel construction.

Fig. 8 is an enlarged vertical sectional view showing the hydraulic pump.

Fig. 9 is a detail sectional view taken substantially on line 9—9 of Fig. 3.

In this illustrative embodiment of the invention there is shown a transport truck, generally designated 1, of improved construction, comprising a rigid truck frame 2 mounted on and propelled by traction means, herein truck wheels 3 adapted to run along a mine trackway 4, and having a tilting front pan or ramp 5. The truck frame consists of parallel machine-receiving and guiding frame members 6, 6 held in rigid spaced relation by transverse frame members 7, 7, and these frame members 6, 6 carry usual axle boxes 8 in which the truck wheel axles 9 are journaled. The tilting ramp 5 is pivotally connected at 10 to the forward end of the rigid truck frame 2, and consists of a bottom supporting plate 11 having upstanding guide flanges 12 at the sides thereof, these guide flanges being flared outwardly at the forward end of the ramp to provide a relatively wide opening to facilitate movement of the mining machine onto the ramp, and this bottom plate is formed with a projecting frame portion 13 in the form of operating means, so that when the machine moves upwardly over the inclined bottom of the ramp onto the rigid truck frame, the machine, as it passes over the operating portion 13, effects tilting of the ramp upwardly from its lower dotted-line position shown in Fig. 2 to its raised transport position indicated in full lines in Fig. 2. The frame members 6, 6 of the rigid truck frame 2 are formed with upstanding guide flanges 14, 14 at the sides thereof, cooperating with the guide flanges 12, 12 on the ramp for guiding the machine as it moves relative to the truck. The coal mining machine is indicated in construction lines at 15 in Fig. 2, and may be of the same general character as that described in a copending application, Serial No. 71,653, filed March 30, 1936, now matured into Patent No. 2,131,178, although it may be evident that the improved transport truck may carry coal mining machines of various other types.

As described in the copending application above referred to, the mining machine transmission has a longitudinal transmission shaft 16 driven under friction control, and secured to the rear end 45 of this shaft by a screw 17 is a coupling member 18, herein arranged within an annular housing 19 formed integral with the rearward portion of the machine frame. This annular housing has a tapered exterior portion 20 adapted to cooperate 50 with a corresponding tapered interior bore 21 formed on a housing 22 secured, as by screws 23, to a gear housing 24 mounted on the rearward portion of the truck frame. As the machine moves rearwardly onto the truck, the tapered 55

portion of the housing 19 is received within the tapered bore of the housing 22 so that the coupling parts are automatically alined as the machine assumes its transport position on the truck. 5 As shown in Fig. 4, the coupling member 18 has formed therein internal clutch teeth 25 slidingly interlocked with clutch teeth 26 formed on the forward end of an axially movable coupling member 27, herein guided within a chamber 28 formed within a rotatable truck driving member 29. The rearward portion of this axially movable coupling member 27 is formed with clutch teeth 30 slidingly interlocked with internal clutch teeth 31 formed on the member 29. A ring 32 seated within a groove formed within the member 29 provides a stop with which the forward ends of the clutch teeth 30 on the member 27 are engageable for limiting outward movement of the coupling member 27. Interposed between the member 29 and the axially movable coupling member 27 is a coil spring 33 for urging the coupling member 27 into its outermost position against the stop ring 32, as shown in Fig. 4. When the coupling member 18 is moved into coupled relation with respect to the member 29, the clutch teeth 25 thereon, in the event of non-alinement with the teeth 26, will move the coupling member 27 rearwardly against the tension of the coil spring to the position shown in Fig. 5 until the teeth 26 are brought into registry with the teeth 25, and then the parts are automatically coupled together by the coil spring 33 snapping the coupling member 27 into clutched relation with respect to the member 18. It will thus be seen that an automatic yieldable coupling device is provided between the machine and truck so that when the machine is moved into transport position on the truck, the truck driving member on the machine is coupled automatically to the truck driving member on the truck.

As shown in Fig. 4, the truck driving member 29 is journaled in ball bearings supported within the housing 22 and has formed thereon at its rearward end a bevel gear 34 meshing with reverse bevels 35 and 36, herein journaled on ball bearings 37 supported by a horizontal shaft 38, herein extending transversely of the truck and suitably journaled in ball bearings 39 supported within the gear housing 24. The bevel gears 35, 36 constitute a reversing mechanism and are selectively connectible in driving relation with the shaft 38 by means of a sliding jaw clutch 40 splined to the shaft 38 and having clutch teeth engageable with the clutch teeth on the adjacent inner faces of the bevel gears. The clutch 40 is operated by means of a shipper yoke 41 having a suitable operating handle 42. Keyed to the shaft 38 is a chain sprocket 43 connected by an endless chain connection 44 to a chain sprocket 45 keyed to the rear truck wheel axle 9. The front and rear truck wheel axles 9, 9 are connected in driving relation by a chain and sprocket connection 46. It will thus be seen that when one or the other of the bevel gears 35, 36 is connected by the clutch 40 to the shaft 38 and the automatic coupling between the machine and truck is connected, the truck wheels may be driven from the drive shaft 16 of the mining machine through the coupling elements, bevel gear 34, one of the reverse bevels 35, 36, shaft 38, and the chain and sprocket connection 43, 44, 45. Keyed to the end of the shaft 38, opposite from the chain sprocket 43, is a brake drum 47 with which cooperates a brake band 48 having a suitable operating handle 49,

and this brake is operable to brake rotation of the truck wheels in an obvious manner.

Now referring to the improved cable reel, generally designated 50, it will be noted that mounted on a rearwardly projecting platform 51 integral with the rigid truck frame 2, for rotation about a vertical axis, is a cable reel 50 for the power conductor cable 53 of the mining machine motor. This cable reel is arranged in a relatively low horizontal position below the top surface of the truck, and is relatively narrow in a vertical direction and of a diameter substantially greater than the height and substantially equal to the width of the truck. This cable reel comprises a drum 54 having its hub 55 journaled on ball bearings 56 supported by a vertical shaft 57, herein formed integral with a member 58 rigidly secured to the platform 51. Secured to the upper side of the drum by screws 59 is a detachable plate 60 having its hub 61 journaled on a bearing sleeve 62 supported by a cylindrical bearing support 63 coaxial with the shaft 57 and formed integral with a conduit member 64 rigidly secured to the reel cover 65. This conduit member 64 has passage 66 for receiving the conductor cable 67 leading from the reel to the mining machine motor controller 68 mounted on the truck.

The means for driving the reel from the motor of the mining machine comprises, as shown in Fig. 3, a bevel gear 69 keyed to and driven by the shaft 38 and meshing with a horizontal bevel gear 70 formed integral with a vertical shaft 71, herein journaled within ball bearings 72 supported within the gear housing 24. The lower end of the shaft 71 has a reduced portion projecting within a bore formed in the hub of a chain sprocket 73, the chain sprocket hub being journaled in ball bearings likewise supported within the gear housing. The reduced lower end of the shaft 71 carries a pawl 74 (see Fig. 9) yieldably held by a spring pressed plunger 75 in engagement with a ratchet tooth 76 formed within the sprocket hub. The chain sprocket 73 is connected by an endless drive chain 77 to a chain sprocket 78 (see Fig. 6) coaxial with the cable reel beneath the latter and secured by screws 79 to drive a member 80 journaled on a ball bearing 81 supported by the vertical shaft 57. The member 80 has a flange 82 supporting an annular friction clutch and retarding plate 83 frictionally engageable with a lower annular plane surface 84 on the cable reel drum 54, and this friction plate provides a friction drive for the cable reel and acts to frictionally resist cable reel rotation when the latter is disconnected from its drive. When the truck is propelled forwardly along the mine trackway as it enters a room off from the main mine entry, the ratchet slips relative to the pawl 74 so that the conductor cable, which is connected to the main power line in the entry, is unwound from the reel, the reel rotating in a direction to pay out the cable under the frictional resistance of the friction plate. When the truck is propelled rearwardly along the room trackway toward the entry, the pawl 74 engages the ratchet tooth 76, and, as a result, the cable reel is driven by power in a direction to wind in the conductor cable. It is accordingly evident that the ratchet and pawl afford a unidirectional drive for the cable reel, so that the reel can be rotated by power in only one direction irrespective of the direction of the drive of the truck wheels.

Means is provided for lifting the cable reel from its frictional engagement with the friction clutch ring 83, comprising a servo-motor having

a hydraulically operated piston 85 reciprocably mounted in a cylinder 86 formed axially within the shaft 57. The upper end of this piston is engageable through a ball thrust bearing 87 with an upper plate 88 integral with the cable reel drum hub 55. Mounted on the truck frame is a pump cylinder 89 having a bore 90 in which is reciprocably mounted a piston 91 provided with a suitable cup packing 92. Also guided in the bore 90 is a plunger 93 having openings 94 connecting the space above the plunger 93 with the space below the same, and interposed between the upper surface of this plunger and the packing 92 is a member 95. Interposed between the bottom of the plunger 93 and a plug 96 threaded within the lower end of the bore 90, is a coil spring 97 for urging the piston 91 into its uppermost position. Threaded at 98 within the top cylinder head 99 is an adjusting screw 100 having an operating handle 101. A conduit 102 connects a passage 103 communicating with the lower end of the pump cylinder with a passage 104 communicating with the cylinder bore 86 below the hydraulic piston 85. When the pump piston 91 is moved downwardly by the adjusting screw against the tension of the coil spring, liquid under pressure is forced from the cylinder bore 90 through the passage 103, conduit 102 and passage 104, to the cylinder bore 86 below the hydraulic piston 85, thereby effecting movement of the latter upwardly to lift the cable reel from the position shown in Fig. 6 to the position shown in Fig. 7, and as a result the cable reel is disconnected from frictional engagement with the friction clutch ring 83, so that at that time the cable reel may be freely manually rotated. When the cable reel is so raised, the operator may grasp the conductor cable 53 and freely unwind the cable from the cable reel. When the cable reel is in its lowered position, in frictional engagement with the friction clutch ring, inadvertent unwinding of the conductor cable due to free rotation of the cable reel is prevented, due to the drag of the friction. The friction clutch ring 83 also provides a frictional driving connection between the drive sprocket 78 and the cable reel, so that when the cable reel is in its lowered position, in engagement with the friction ring, the cable reel may be driven by power from the motor of the mining machine from the coupling mechanism 18, 27, 29, bevel gear 34, one or the other of the reverse bevels 35, 36, shaft 38, bevel gearing 69 and 70, and the chain and sprocket connection 73, 77 and 78. When the cable reel is lifted by the hydraulic piston out of engagement with the friction plate 83, the drive between the chain sprocket 78 and the cable reel is, of course, interrupted.

The mining machine 15, as described in the co-pending application above referred to, is of the room and pillar, floor cutter type, comprising relatively rotatable feeding and controlling drums each respectively cooperating with flexible feeding and controlling cables. During the loading of the machine onto the truck, one of the cables is extended from its drum to a hook 105 (see Figs. 1 and 3) formed integral with the gear housing 24, and as the drum is rotated by power from the motor of the mining machine, the cable is wound in, thereby moving the machine rearwardly up over the ramp and onto the truck; and when the motor of the mining machine is stopped by the controller 68 on the truck, rotation of the drum is frictionally resisted by its driving transmission, so that the machine is held in

transport position on the truck by the feed cable connected to the hook 105. When it is desired to unload the machine from the truck, one or the other of the cables is extended from a drum on the machine and connected to one of the hooks 106 secured to the sides of the tiltable loading ramp 5, as shown in Fig. 1, so that when the cable is drawn in by its drum by power from the motor of the machine, the machine is moved forwardly off from the truck. As the machine moves forwardly from the truck, the ramp 5 tilts downwardly to the dotted-line position shown in Fig. 2, so that the machine may move thereover from the truck onto the mine floor. Supported at the sides of the platform 51, at the rearward end 15 of the rigid truck frame 2, are platforms 107 and 108 on which the machine operator and his helper may ride during movement of the truck about the mine from one working place to another; and projecting from the sides of the controller housing are rail-like handles 109 which may be grasped to enable the machine operator and his helper to retain their positions on the platforms. It will be noted that the handle 110 of the motor controller and the clutch handle 42 and the brake 25 handle 49 are located above the platform 108 on which the machine operator rides, so that movement of the truck about the mine may be readily controlled by the operator.

As a result of this invention, it will be noted 30 that an improved transport truck for a coal mining machine is provided, whereby the machine may be readily loaded and unloaded onto and off from the truck, and which has improved automatic coupling means whereby when the machine is moved into its transport position onto the truck, the truck driving element on the machine is automatically connected to the truck driving element on the truck. It will further be noted that an improved cable reel is provided, 35 having improved driving and controlling means therefor, whereby the power conductor cable may be wound in or paid out by power, and having improved reel-lifting means whereby the cable reel drive may be disconnected so that the cable 40 may be freely manually unwound from the drum. Other uses and advantages of the improved transport truck will be clearly apparent to those skilled in the art:

While in this application there is specifically 50 described one form which the invention may assume in practice, it will be understood that this form is shown for purposes of illustration only, and that the invention may be modified and embodied in various other forms without departing 55 from its spirit or the scope of the appended claims.

What I claim as new and desire to secure by Letters Patent is:

1. In a mining machine transport truck, the 60 combination comprising a truck frame adapted to receive a mining mechanism having a driving motor, a cable reel mounted on said truck frame and having wound thereon a power conductor cable for said motor, motor operated means for 65 rotating said cable reel, and a servo-motor for moving said cable reel axially to disconnect the reel from its rotating means.

2. In a mining machine transport truck, the 70 combination comprising a truck frame adapted to receive a mining mechanism having a driving motor, a cable reel mounted on said truck frame and having wound thereon a power conductor cable for said motor, motor operated means for 75 rotating said cable reel, and a hydraulic servo-

motor comprising a hydraulically operated piston for moving said cable reel axially to disconnect said reel from its rotating means.

3. In a mining machine transport truck, the combination comprising a truck frame adapted to receive a mining mechanism having a driving motor, a horizontal cable reel rotatable about a vertical axis, said reel mounted on said truck frame and having wound thereon a power conductor cable for said motor, motor operated means for rotating said cable reel, and a servo-motor for lifting said reel to disconnect the reel from its rotating means.

4. In a mining machine transport truck, the combination comprising a truck frame adapted to receive a mining mechanism having a driving motor, a horizontal cable reel rotatable about a vertical axis, said reel mounted on said truck frame and having wound thereon a power conductor cable for said motor, motor operated means for rotating said cable reel, and a hydraulic servo-motor comprising a hydraulically operated piston for lifting said cable reel to disconnect said reel from its rotating means.

5. In a mining machine transport truck, the combination of a truck frame adapted to receive a mining mechanism having a driving motor, a horizontal cable reel mounted on said truck frame for rotation about a vertical axis and having wound thereon a power conductor cable for said motor, motor operated means for driving said reel including a friction driving device including frictional driving means through which said reel is driven, and means for interrupting reel drive comprising a servo-motor for lifting said reel to disconnect said reel from said frictional driving means.

6. In a mining machine transport truck, the combination comprising a truck frame adapted to receive a mining mechanism having a driving motor, a horizontal cable reel rotatable about a vertical axis, said reel mounted on said truck frame and having wound thereon a power conductor cable for said motor, motor operated means for rotating said cable reel including a friction drive means coaxial with the reel, and a hydraulic servo-motor comprising a hydraulically operated piston for lifting said cable reel to release said frictional driving means to disconnect said reel from said rotating means.

7. In a mining machine transport truck, the combination with a truck driving element on the machine and a truck driving element on the truck of a horizontally disposed automatic self-aligning coupling mechanism for automatically connecting said truck driving element on the truck in driving relation with said driving element on the machine as the latter is moved horizontally into its transport position on the truck.

8. In a mining machine transport truck, the combination with a truck driving element on the machine and a truck driving element on the truck, of an automatic self-aligning coupling mechanism for automatically connecting said truck driving element on the truck in driving relation with said driving element on the machine as the latter is moved into its transport position on the truck, said coupling mechanism including self-aligning elements and a yieldably mounted axially movable coupling element coaxial therewith for automatically connecting said driving elements together when the machine is moved into its transport position.

9. In a mining machine transport truck, the combination with a truck driving element on the

machine and a truck driving element on the truck, of an automatic self-aligning coupling mechanism for automatically connecting said truck driving element on the truck in driving relation with said driving element on the machine as the latter is moved into its transport position on the truck, said coupling mechanism including self-aligning elements and a yieldably mounted axially movable coupling element coaxial therewith for automatically connecting said driving elements together when the machine is moved into its transport position, said coupling element automatically yieldable in the event of misalignment of said driving elements.

10. In a mining machine transport truck the combination with a truck driving element on the machine and a truck driving element on the truck of an automatic self-aligning coupling mechanism for automatically connecting said truck driving element on the truck in driving relation with said driving element on the machine as the latter is moved into its transport position on the truck, said coupling mechanism including cooperating self-aligning elements and a yieldably mounted axially movable coupling element coaxial therewith for automatically connecting said driving elements together when the machine is moved into its transport position, said coupling element automatically yieldable in the event of misalignment of said driving elements, and a spring for automatically moving said coupling element into its connecting position when said driving elements are brought into alignment.

11. In a mining machine transport truck, a truck frame adapted to receive a mining machine for transport, the machine having cutting means and a driving motor for the cutting means, a cable reel mounted on said truck and having wound thereon a power conductor cable for the mining machine motor, motor operated means for rotating said cable reel, and a servo-motor for moving said cable reel axially to disconnect said reel from its rotating means.

12. In a mining machine transport truck, a truck frame adapted to support a mining machine, the machine having cutting means and a driving motor for the cutting means, a cable reel mounted on said truck frame and having wound thereon a power conductor cable for the mining machine motor, means driven by said motor when the machine is supported on the truck for rotating said cable reel, and a servo-motor for moving said cable reel axially to disconnect said reel from its rotating means.

13. A mining machine transport truck, a truck frame adapted to receive a mining machine for transport, a cable reel mounted on said truck frame and having wound thereon a power conductor cable, motor operated means for rotating said cable reel, and a servo-motor for moving said cable reel axially to disconnect said reel from its rotating means.

14. A mining machine transport truck, a truck frame adapted to receive a mining machine for transport, the mining machine having a motor adapted to propel the truck, a cable reel mounted on said truck frame and having wound thereon a power conductor cable for said motor, means driven by said motor when the machine is supported on the truck for rotating said cable reel, and a servo-motor for moving said cable reel axially to disconnect said reel from its rotating means.

15. In a mining machine transport truck, the combination with a truck driving element on a

- mining machine to be transported and a truck driving element on the truck, of an automatic self-centering yieldable coupling having self-centering coupling means for automatically centering said elements and for connecting said truck driving element on the truck in driving relation with the driving element on the machine as the latter is moved into its transport position on the truck.
5. 16. In a mining machine transport truck, the combination with a truck driving element on a mining machine to be transported and a truck driving element on the truck, of an automatic self-centering yieldable coupling arranged with 10 its axis extending longitudinally of the truck parallel to the path of movement of the machine on the truck and having self-centering coupling means for automatically centering said elements and for connecting said truck driving element on 15 the truck in driving relation with the driving ele- ment on the machine as the latter is moved into its transport position on the truck.
17. In a mining machine transport truck, the combination of a truck frame adapted to receive, a mining mechanism having a driving motor, a horizontal cable reel mounted on said truck frame for rotation about a vertical axis and having wound thereon a power conductor cable for said motor, motor operated means for driving said reel including a friction driving device including frictional driving means through which said reel is driven, and means for interrupting reel drive comprising a servo-motor for lifting said reel to disconnect said reel from said frictional driving means the weight of said cable reel resting on said frictional driving means when said servo-motor is inactive effecting the frictional driving connection between said driving means and said reel. 20

JOSEPH F. JOY. 20

CERTIFICATE OF CORRECTION.

Patent No. 2,161,818.

June 13, 1939.

JOSEPH F. JOY.

It is hereby certified that error appears in the printed specification of the above numbered patent requiring correction as follows: Page 2, second column, line 25, after the word "has" insert a; line 47, for "to drive a" read to a drive; page 4, first column, line 34, claim 5, for "drven" read driven; line 54, and second column, lines 15 and 18, claims 7 and 10 respectively, after "truck" insert a comma; page 5, second column, line 4, claim 17, strike out the comma after "receive"; line 15, same claim, after "means" insert a comma; and that the said Letters Patent should be read with this correction therein that the same may conform to the record of the case in the Patent Office.

Signed and sealed this 3rd day of October, A. D. 1939.

Henry Van Arsdale,
(Seal) Acting Commissioner of Patents.
